(57) **CLAIM**

The ornamental design for a stand, as shown and described.

DESCRIPTION

In a preferred embodiment, the nature of this product is as a pedestal primarily useful for mounting a plumbing fixture such as a lavatory.

FIG. 1 is a left, top, front perspective view of a stand embodying our new design;

FIG. 2 is a front elevational view thereof;

FIG. 3 is a left side elevational view thereof, the right side

elevational view being a mirror image of the left side shown;

FIG. 4 is a top plan view thereof; and,

FIG. 5 is a bottom plan view thereof.

The broken line representations of holes in FIGS. 1, 4, and 5, of a lavatory bowl in FIGS. 1 and 5, and of support structure in FIG. 5, are for the purpose of illustration only, and form no part of the claimed design.
